UNITED STATES PATENT OFFICE.

GEORGE M. WILLIAMS, OF ELIZABETH, NEW JERSEY, ASSIGNOR TO P. LORILLARD COMPANY, OF NEW YORK, N. Y., A CORPORATION OF NEW JERSEY.

SEALING MEANS FOR PACKING AND SHIPPING CASES.

1,287,546.

Specification of Letters Patent. Patented Dec. 10, 1918.

Application filed June 16, 1914. Serial No. 845,358.

To all whom it may concern:

Be it known that I, GEORGE M. WILLIAMS, a citizen of the United States, residing at Elizabeth, in the county of Union and State 5 of New Jersey, have invented new and useful Improvements in Sealing Means for Packing and Shipping Cases, of which the following is a specification.

My present invention relates generally to 10 packing and shipping cases in which articles of merchandise are packed and shipped and has to do more particularly with an improved means for fastening and sealing the overlapping ends of the metallic straps usually employed to bind such cases, with the 15 object in view of minimizing losses that frequently occur through unauthorized opening of and thefts from the cases by unscrupulous persons during transit thereof from the manufacturer to the customer, jobber or retailer.

It is a well recognized fact among manufacturers and shippers generally that thousands of dollars worth of goods are lost annually by reason of the unauthorized opening of shipping cases and petty thefts therefrom by unscrupulous persons, who, after prying up a board or boards of the shipping case remove a small portion of the contents thereof and then replace the said board or 20 boards in order to restore the case to its original condition, so far as its external appearance is concerned. These thefts usually occur while the boxes or cases are in transit from the shipper to the customer, and as the 25 cases, so far as external appearance is concerned, bear no mark or evidence indicating that they have been tampered with, that fact is not discovered until the case has been opened by the customer, and this then raises 30 a question between the shipper and his customer as to whether or not the case was, as a matter of fact fully packed when it left the shipper; whether it was opened in transit, or whether the customer is entirely correct or truthful in his complaints as to shortage, which questions are often difficult of 35 satisfactory adjustment and usually result in the shipper having to stand the loss.

The object of the present invention is to 40 provide a novel and simple form of seal for the overlapping ends of the straps or bands that encircle the packing case and one that will readily betray the fact as to whether or not the case has been opened in transit, it 45 being the duty of the shipper to see that the

case is in proper shape and properly packed before it leaves his hands.

A further object of the invention is to provide a seal for the purpose stated that cannot be removed, after having once been inserted and set, without so distorting, marring, or breaking it as to render its undetectable reuse a practical impossibility.

The invention has in view other more or less important objects, all of which will be 65 made clear in the detailed description to follow.

Briefly and generally stated my improved seal consists of an eyelet-like structure made of 70 relatively thin and comparatively soft metal and comprising a relatively broad and thin disk-like plate with an opening therethrough from the perimeter of which opening extends a circular flange or sleeve, the latter being preferably provided with a plurality of 75 longitudinally extending slits or cuts to facilitate the swaging operation when the said flange or sleeve is passed through aligned openings in the overlapping ends of a box strap, the said relatively broad disk-like 80 plate being employed in order to provide a face upon which may be impressed or otherwise delineated in a conspicuous manner, the name, initials, or trade-mark of the manufacturer or shipper, and the word "seal", showing 85 that the box or package has been sealed.

I have illustrated in the accompanying drawing a preferred embodiment of the invention, wherein—

Figure 1 is a perspective view of a box 90 bound with metal straps, the overlapping ends of which are sealed according to the invention.

Fig. 2 is a side elevation of the sealing eyelet.

Fig. 3 is a top plan view of the eyelet.

Fig. 4 is a bottom plan view showing the swaged end of the eyelet.

Fig. 5 is a sectional view showing the eyelet in position before being swaged, and

Fig. 6 is a similar view showing the eyelet after being swaged.

Referring to the said drawings the reference numeral 10, designates a shipping box or case which, in the instance shown, is of 105 ordinary construction and comprises wooden ends 12, and top, bottom and sides, the latter preferably consisting of wooden strips 13, as shown. Obviously the box or case may be otherwise constructed without de-

95

100

110

parting from the spirit of the invention, the showing here being merely illustrative.

The said box or case is bound by a metal strap or straps 14, secured thereto at intervals by means of nails 15, as is usual. The ends of the strap or straps are overlapped preferably upon the top wall of the box or case and an opening 16 punched through said overlapping ends as more clearly shown 10 in Figs. 5 and 6.

My improved seal consists of an eyelet-like member preferably formed from thin and comparatively soft metal, such as brass, and comprises a thin disk-like plate 17, having a relatively broad face upon which I propose to imprint, stamp or impress the word "seal" or some similar designation, together with the name, initials or trademark of the manufacturer or shipper of the 20 goods contained within the box or case, all as more clearly shown in Fig. 3.

The said disk-like plate 17, is provided with an opening from the perimeter of which opening extends a sleeve or collar 18, 25 formed integral with the plate, the said sleeve being provided with a plurality of slits or incisions 19, extending longitudinally thereof from its outer end inward toward, but preferably terminating short of the said plate, as more clearly shown in Figs. 2 and 5, the said slits or incisions forming between them clenching or swaging tongues 20, as more clearly shown in Figs. 4 and 6.

35 In applying my improved seal the strap 14, is first secured to the box in the manner hereinbefore referred to and as illustrated in Fig. 1, and the aligned openings 16, are then punched or cut therein, said openings 40 being preferably slightly larger than the sleeve portion 18 of the eyelet for a purpose presently to be explained and said openings being preferably located at a point removed from the end 21 of the upper lap of the 45 strap which upper lap is secured at its said end 21, to the box or case by means of a nail 22, as illustrated in Fig. 1.

After the openings 16, have been formed in the overlapping ends of the strap, the 50 sleeve portion 18, of the sealing eyelet is inserted therein and the slitted end upset or swaged over the lower face of the under lap of the strap so that the tongues 20 will be radially spread as illustrated in Fig. 4, 55 and the said tongues will closely overlie the upper face of one of the board strips 13 constituting a portion of the top or side wall of the box or case as more clearly shown in Fig. 6. The swaging or upsetting operation 60 is effected by means of a tool having an anvil member with which the incised end of the sleeve 18 engages, the said anvil member serving to spread the tongues and cause them to closely embrace the lower face of 65 the under lap of the strap upon a hammer-

blow being imparted to the disk-like face of the sealing member. The tool referred to forms no part of the present invention, but is shown and described in my co-pending application filed of even date herewith 70 (forming the subject-matter of Patent No. 1,123,153).

The openings 16, in the overlapping ends of the strap are made slightly larger than the sleeve portion 18 of the eyelet in order 75 to leave sufficient clearance between the sleeve and wall of the opening so that during the operation of swaging or setting the eyelet the sleeve portion will be slightly crimped or distorted laterally as more clearly shown 80 in Fig. 6. This crimping or distorting of the sleeve taken in connection with the fact that the eyelet as a whole is made of thin and comparatively soft metal, will render unauthorized reuse thereof practically impossible as any attempt to remove the same 85 from its connection with the strap after it has been once set will result in such distortion of the eyelet as to practically destroy it. If an eyelet of some other form, and 90 one not bearing the name, initials or trademark of the manufacturer or shipper of the box, should be substituted for the original one the customer upon receiving the box or case would know at once that the seal had 95 been broken in transit and in such a case he would return the box without opening it.

I prefer to slit or incise the sleeve portion of the eyelet-like sealing member in order to insure a better and more uniform upsetting 100 of said member. I also prefer to upset the sleeve upon the under lap of the strap so that the upset tongues will be confined between the strap and a wall of the box, thus making it practically impossible for any one 105 to straighten out the prongs after they have once been set, in an attempt to withdraw the sealing member, with the idea in mind of reinserting and resetting the same after having removed a portion of the contents 110 of the box. The fact that the sealing member is made from relatively thin and comparatively soft sheet metal, makes removal thereof without destruction, a practical impossibility. It will be apparent therefore 115 that the security of my improved method of sealing box straps resides to a great extent in the weakness or frail construction of the sealing member.

I am aware that it has been proposed 120 heretofore to fasten the overlapping ends of box straps by means of solid as well as hollow rivets; but these have not proven satisfactory because of the fact that they can be readily removed by filing away the swaged 125 end and then reset, or a new rivet may be substituted for the one removed. Since my improved sealing member bears the name, initials or trade-mark of the manufacturer or shipper, the substitution for such a 130

marked member of one not so marked will readily betray the fact that the box or package has been tampered with in transit.

If desired I may drive a nail 23 or other 5 fastening device through the opening in the sealing member as shown in Fig. 6, so that the head of the nail will overlie the face of the plate 17, around the margin of the opening, thus if an attempt is made to open the seal it will be necessary to first withdraw 10 the nail, and owing to the fact that the top plate 17, of the sealing member is thin and made of comparatively soft metal, the operation of drawing the nail will so scar or 15 otherwise rupture the said plate as to make it apparent that the sealing member has been tampered with.

I prefer to locate the sealing member at a point somewhat removed from the end 21, 20 of the upper lap of the strap in order to facilitate authorized breaking of the seal, which may be easily accomplished by first withdrawing the nail 22, to free the said end 21, of the strap, thus providing a grasping 25 portion, which when pulled upwardly, will break or rip open the sealing member, this being possible because of the nature of the material from which the sealing member is made. Furthermore, this particular location 30 of the sealing member places it in position where it is substantially free from shearing or other distorting strains, thus preserving the integrity of the member under shipping conditions, even though the 35 member is so formed as to be easily damaged or distorted under these strains when permitted by removing nail 22.

What I claim is:—

1. A shipping package comprising a receptacle having a metallic sealing strap encircling the same and secured thereto at intervals throughout its length, the ends of 40 said strap overlapping each other, and means for detecting surreptitious release of the secured strap to permit opening of the receptacle, said means including registering 45 openings in said strap end portions, said openings being spaced from the free end of the upper lap of the strap, a hollow sealing member 50 eyelet having a sleeve portion extending through said openings in the strap with the marginal edges of said sleeve portion swaged over the face of the under lap of the strap and lying between said face and a 55 wall of the receptacle, and securing means located at the end of the upper lap of the strap beyond the eyelet, whereby the detecting means will be carried solely by the overlying strap ends and will be normally retained 60 free from shearing or distorting strains.

2. A shipping package comprising a receptacle having a metallic sealing strap encircling the same and secured thereto at intervals 65 throughout its length, the ends of

said strap overlapping each other, and means for detecting surreptitious release of the secured strap to permit opening of the receptacle, said means including registering 70 openings in said strap end portions, said openings being spaced from the free end of the upper lap of the strap, a hollow sealing eyelet having a sleeve portion extending through said openings in the strap with the marginal edges of said sleeve portion 75 swaged over the face of the under lap of the strap and lying between said face and a wall of the receptacle, the head of said eyelet overlying the upper lap of the strap being relatively broad and bearing a suitable 80 mark indicating the source from which the receptacle came, and securing means located at the end of the upper lap of the strap beyond the eyelet, whereby the detecting 85 means will be carried solely by the overlying strap ends and will be normally retained free from shearing or distorting strains.

3. A shipping package comprising a receptacle having a metallic sealing strap encircling the same and secured thereto at intervals throughout its length, the ends of 90 said strap overlapping each other, and means for detecting surreptitious release of the secured strap to permit opening of the receptacle, said means including registering 95 openings in said strap end portions, said openings being spaced from the free end of the upper lap of the strap, a hollow sealing member consisting of a relatively thin plate having a broad face and an integrally 100 formed sleeve or collar, the latter extending through the openings in the strap with the marginal edges thereof swaged over the face of the under lap of the strap and lying between said face and a wall of the receptacle, 105 said broad face of the sealing member bearing a mark indicative of the source from which the receptacle came, and securing means located at the end of the upper lap of the strap beyond the sealing member, whereby the detecting means will be carried solely by the overlying strap ends and will be normally retained free from shearing or 110 distorting strains.

4. A shipping case comprising a receptacle having a metallic strap encircling the same and secured thereto at intervals throughout its length, the ends of the strap overlapping each other and secured to the receptacle within such overlapping portions, 115 and means for detecting surreptitious release of the secured overlapping ends to permit opening of the receptacle, said means including registering openings in said strap end portions, said openings being positioned beyond such point of end securing to locate the latter point between the openings and the end of the outer portion of the overlapped ends, and a sealing member consisting of a relatively thin and comparatively 120

130

soft metallic plate having a broad face with an opening therethrough and an integrally formed sleeve outstanding from the plate around said opening, said sleeve being 5 slightly smaller than and extending through the openings in the strap and having its marginal edges swaged over the face of the under lap of the strap and lying between said face and a wall of the receptacle, said sleeve being laterally distorted when the eyelet is swaged in position to unite the ends of the strap, the said broad face of the plate of the sealing member bearing a mark indicating the source from whence the receptacle 10 came, whereby the detecting means will be carried solely by the overlapping strap ends and will be normally retained free from shearing or distorting strains.

5. A shipping case comprising a receptacle having a metallic strap encircling the same and secured thereto at intervals throughout its length, the ends of the strap overlapping each other and secured to the receptacle within such overlapping portions, and means for detecting surreptitious release of the secured overlapping ends to 15 permit opening of the receptacle, said means including registering openings in said strap end portions, said openings being positioned beyond such point of end securing to locate the latter point between the openings and the end of the outer portion of the overlapped ends, and a hollow sealing member 20 consisting of a thin plate of soft metal having a broad face with an opening therethrough, and an integrally formed and lon-

gitudinally incised sleeve also of soft metal outstanding from the plate around said opening, said sleeve extending through the said openings in the strap, such sleeve being laterally distorted when the sealing member is swaged in position to unite the ends of the strap, and having the portions thereof between the incisions upset over the face of the under lap of the strap and lying between said face and a wall of the receptacle, whereby the detecting means will be carried solely by the overlapping strap ends and will be normally retained free from shearing or distorting strains. 25

6. As a means for detecting surreptitious opening of shipping packages having encircling metallic sealing straps secured to the packages with overlapping ends, a sealing member of eyelet form extending through the overlapping ends at a point where shearing strains will be ineffective, and securing means located at the end of the upper lap of the strap beyond the sealing member, said eyelet being formed of thin 30 soft metal with the inner end swaged and underlying the strap and with the outer face of such swaged end external of and in proximity to a wall of the package. 55

In testimony whereof I have hereunto set my hand in presence of two subscribing witnesses. 60
